CONTAINER CONSTRUCTION

Philip E. de Merce, Los Angeles, Calif.

Application July 17, 1933, Serial No. 680,721

3 Claims. (Cl. 220—15)

This invention relates to the construction of a barrel or container adapted for a variety of uses but more particularly intended for the purpose of containing and transporting explosives, chemicals and beverages.

An object of the invention is to provide improved temperature-insulating means which is adapted, for a long period of time, to maintain the contents of the container at approximately the same temperature, whether hot or cold, which it possesses at the time of being placed within the container.

Another object of the invention is to provide a container with shock absorbing means surrounding its contents, thus adapting the container for the shipment of explosives of the kind which need to be safeguarded against being exploded by percussion.

A still further object of the invention is to furnish the container with means to surround its contents which is of a yielding resilient nature in order that internal pressure from the contents of the container will be less apt to rupture the wall thereof at any point.

Although the invention is illustrated as applied to a container of a barrel shaped or drum shaped character, yet it is to be understood that, broadly considered, the construction thereof may be applied to containers of other shapes than those illustrated in the drawing.

Other objects, advantages and features of the invention may hereinafter appear.

Referring to the accompanying drawing which illustrates what is at present deemed to be a preferred embodiment of the invention,

Fig. 1 is a side view, partly in elevation and partly in section, illustrating a drum shaped container constructed according to the principles of the invention.

Fig. 2 is a sectional detail taken on the plane indicated by the line 2—2 of Fig. 1.

Fig. 3 is an enlarged reproduction of a right hand portion of Fig. 1.

Fig. 4 is a side view, partly in section and partly in elevation, showing the invention applied to a barrel shaped container.

Referring in detail to the drawing, in Figs. 1, 2 and 3 is shown a drum shaped container having an outer cylindrical side wall 5 which will ordinarily be made of sheet metal, and a cylindrical side wall 6 in inwardly spaced relation to said wall 5 and preferably also made of sheet metal. The space between these two walls will be filled with a suitable heat insulating material 7 such as mineral wool or asbestos.

One end of the container is provided with a fixed head or closure member 8 and the other end thereof is provided with a removable head or closure member 9. The closure member 8 is furnished with an outer sheet metal wall 10 which has an outwardly directed cylindrical flange 11 which is fitted tightly within the adjacent end portion of the cylindrical outer shell or wall 5. The end portion of this wall 5 and the edge portion of the flange 11 are crimped together at 12 in a well known manner to form an effective fluid-tight connection.

An important feature of the invention consists in various shock absorbing insulating means which are interposed between the inner and outer walls. One of these elements consists of an annular rubber ring 13 which is seated upon the inner surface of the end wall 10 and is held in place between an annular outer angle iron flange 14 and a cooperating inner annular angle iron flange 15, these angle iron flanges having their foot portions welded or otherwise secured to the inner side of the end wall 10. Said rubber ring 13 is provided along the midwidth of its inner face with a trough or depression 16 within which is seated the adjacent end portion of the inner sheet metal member 6 and within which is also seated the outwardly directed cylindrical flange 17 of an inner head or wall 18 which is in spaced relation to the wall 10 of the head 8. The space between the walls 10 and 18 is likewise filled with insulating material 19 such as mineral wool or asbestos.

In the drawing the containers shown are adapted to contain and dispense a beverage. A bung hole 21 is therefore provided, this bung hole being surrounded by a metal sleeve 22 provided with an external outwardly directed flange 23 which seats upon a fiber gasket 24. This gasket is of an annular character and is seated within an annular depression or groove 25 which is formed by depressing the adjacent part of the sheet metal wall 5.

The sleeve 22 is provided with a thick body portion which furnishes an inwardly directed shoulder 26. This shoulder 26 seats upon a shock absorbing gasket 27 which is interposed between said shoulder and an internally threaded ring 28 which is loosely seated in an annular depression in the internal wall 6. Said ring 28 is provided with an outwardly directed base portion or foot 29, and the wall 6 is provided with a deflected lip 30 thereby forming an annular recess to receive the foot portion of said ring 28. The metal sleeve 22 is provided with a screw threaded inner

portion which cooperates with the threads of the ring 28 in order that when the part 22 is screwed into place the gasket 27 will be compressed between the shoulder 26 and the ring 28.

5 Above and below the bung hole 21 are provided the steel reinforcing rings which firmly engage the outer surface of the inner wall 6.

In the lower portion of Fig. 3 is shown a spigot sleeve 32 which is flanged and cushioned in the 10 same manner as the bung hole sleeve 22 and is therefore provided for the most part with the same reference characters. This sleeve, however, is provided with internal screw threads 33 to cooperate with the external screw threads of 15 the spigot, not shown. A removable plug 34 is shown screwed into the opening of said sleeve 32 for the purpose of closing the opening during shipment.

Below the removable head 9 is located in considerably spaced relation thereto a permanent cross head or partition 35 which is provided with a central filling opening 36 surrounded by an internally threaded sleeve 37 and furnished with a screw threaded closure cap 38. In the space between 25 said head 35 and the removable head 9 is located the ice or other refrigerating chamber 39. When said head 9 is in place it is confined to the space circumscribed by the side wall of the barrel. Said wall, in fact, projects slightly 30 beyond the outer face of said head thus protecting the head from injury during all rolling and dropping movements wherein that end of the barrel may come into contact with a supporting surface.

35 To the inner face of the removable head 9 is secured a housing member 40 which is shown constructed as a sheet metal disc having around it a flange 41 which is directed toward and seats upon the inner surface of the head 9. This 40 housing member 40 is shown secured to the head 9 by a plurality of screws 42 furnished with nuts 43. In the space between the member 40 and the head 9 is stuffed a filling 44 of asbestos or other heat insulating material. The fixed partition 35 is located a sufficient distance from the 45 head 9 to provide room for said filling without making the refrigerating chamber 39 too small.

The removable head 9 is furnished with a handle 45 and, may, with respect to its other details, 50 be of any suitable, well known construction. In Fig. 2 is shown in detail the preferred clamping means wherein an inner tapered lug 46 cooperates with an outer tapered lug 47. Said head 9 is thus removably seated within the depressed 55 part of the internal annular flange 48 of a rim member 49 which at 50 overlies and is crimped to the peripheral portion of the adjacent end of the container.

The floor portion 51 of the rim member 49 terminates internally at the riser ring or flange 52. Around said flange 52 is placed the rubber ring 53 said ring having cut into its lower side a kerf which receives the upper edge of the flared end portion 54 of the internal wall of the container.

65 By the construction described, owing to the clamping and crimping fits between the outer cylindrical wall and the outer walls of the heads 8 and 9, the entire outer wall structure of the device is rendered rigid and inelastic; but the inner wall section is cushioned off from the outer wall section in such a manner that whatever substance is contained within the device is considerably protected from shock and vibration during transportation and handling. In the structure 75 illustrated the cylindrical portion of the outer

wall is provided with externally projecting beads 70 extending therearound. These beads are adapted to engage any floor or flat surface upon which the container shown in Fig. 1 may be rolled during handling.

5 In Fig. 4 is shown a modification wherein the container is of a barrel shape being provided with a bulged outer side wall member 60 preferably made of wood, the inner side wall member 61 desirably being made of sheet metal. The space 10 between the members 60 and 61 is stuffed with a filling 62 of mineral wool, asbestos or the like. In the form of the invention shown in Fig. 4 there is also, at the filling end of the receptacle, 15 an internal head or fixed partition 63 furnished with a filling sleeve 64 which is internally threaded to receive a screw cap 65. The removable head 66 thus forms the outer wall of the refrigerating chamber 67. This form of the invention shows a barrel provided both throughout 20 the circumferential extent and at its ends with an exterior wooden wall spaced within which is a metal wall the space between the two walls containing insulated stuffing material. Both forms of the invention are also provided with a 25 refrigerating chamber at the filling end of the container.

Describing further the form of the invention shown in Fig. 4, the construction, like that of Fig. 1 is provided along the inner faces of the 30 end members with annular shock absorbing members 13a and 53a. With regard to the shock absorbing member 13a the downwardly directed flange 17a of the lower metal plate 18a, is seated, under pressure, upon the member 13a while the 35 adjacent end of the inner barrel wall 61 abuts against said flange 17a and also has its edge portion in forcible contact with said shock absorbing member 13a. At the upper end of the barrel the upper edge of the wall 61 abuts against a flange 63a with which the partition 63 is provided and 40 said wall and flange have their edge portions forcibly engaging the shock absorbing ring 53a. Preferably the various shock absorbing rings used in both forms of the invention will be formed of 45 a compressible but firm rubber. Where the edges of the metal plates shown in the drawing forcibly engage this elastic material, depressions will be formed whether or not any groove is previously provided to receive the metal edges of the parts 50 which are stabilized by the shock absorbing rubber elements.

55 So far as the closure head of the barrel shown in Fig. 4 is concerned such of the details thereof as have not been specifically described may be 55 of any well known preferred construction. The wood or similar material of which the side wall of the barrel will ordinarily be constructed, will of itself serve to a considerable extent as a shock absorber. In some respects it will protect the 60 underlying structure more efficiently than would a metallic outer wall.

I claim:

1. In a device of the kind described, a container of a generally cylindrical character having a closure head, the cylindrical and head portion of said container both being formed with inner and outer wall portions in spaced relation to each other, said head having mounted thereon a rubber ring which extends along its circumferential 65 portion, said ring having along its midwidth in its inner face an annular groove, the end portion of the inner wall of said cylindrical portion engaging said recess, and the inner wall of said head being provided with an outwardly directed 70

peripheral flange which fits within the end portion of the inner wall of said cylindrical portion, said flange also resting within said groove.

2. In a device of the kind described, a container of a generally cylindrical character having a closure head, said head being formed with inner and outer wall portions in spaced relation to each other and having mounted thereon a shock absorbing peripheral ring, the adjacent 5 end portion of a wall of said cylindrical portion engaging the inner face of said ring and the inner wall of said head being provided with an outwardly directed flange which fits within the end portion of said wall of said cylindrical portion, 10 and clamping means acting between said head and the cylindrical portion of the container to force the inner face of said ring against the edge of the adjacent portion of the cylindrical part 15 of the container.

3. A barrel having therein a permanent cross head or partition which has a stopper controlled filling opening therethrough and which divides as a whole the space inclosed by the barrel into two chambers, a large inner storage chamber 5 and a relatively small outer refrigerating chamber, there being a removable head provided to close the outer side of said refrigerating chamber, the outer face of the last recited head forming the exterior surface of that end of the barrel, and an annular rim member having a peripheral portion which overlies and is crimped to the peripheral portion of that end of the barrel, said member having a depressed inner portion within which the peripheral portion of said 10 removable head fits.

PHILIP E. DE MERCE.
